APPARATUS FOR MAKING BRUSHES

William F. Enchelmaier, Cedar Grove, N. J.

Application April 18, 1950, Serial No. 156,697

20 Claims. (Cl. 300—2)

This invention relates to an improved, simplified, apparatus for making cylindrical brushes of the type wherein the bristles are held between the turns or convolutions of one or more bristle holding strands, cords, or the like helically wound on the brush core.

Apparatus, of which the present invention is an improvement, in which cylindrical brushes are made in a manner above indicated is shown in each of the patents to Angell, Nos. 1,721,062; 1,824,649; 1,950,379; and 2,061,129. Such Angell patents show typical prior art structures of apparatus for making cylindrical brushes with which the present invention is concerned. In such structures, particularly those which feed the bristles continuously, in untufted relationship, the feeding mechanism for the bristles is complicated, unwieldy, and slow in operation. Furthermore, such bristle feeding mechanism, because of its intricacy, is expensive to maintain.

Accordingly, it is among the objects of the present invention to provide a simple, economical, apparatus, capable of speedy operation, for producing cylindrical brushes of the type wherein the bristles are held between the convolutions of one or more bristle holding strands of cord or the like helically wound on the brush core.

More specifically, in a preferred embodiment of the apparatus of the invention, the invention has as an object the provision of apparatus for producing the brush, in the manner indicated, in which a wheel, positioned with its axis generally normal to the axis of the brush core, is stationed so that the rim of one part of the wheel is generally tangential to the cord being wound on the brush core in the portion thereof first entering upon or engaging the brush core, another portion of the wheel feeding bristles continuously between such entering cord portion and the last laid complete convolution of cord on the core.

Yet another object of the invention lies in the provision, in apparatus of the type above indicated, of a means for driving such cord and bristle feeding wheel and preferably also the means for feeding bristles to said wheel, the wheel and the bristle feeding means being driven by the winding up of the bristle retaining cord or cords on the brush core.

Yet another object of the invention lies in the provision of a simplified means for impregnating the bristle retaining cord or cords and the butt ends of the bristles with curable bristle and cord retaining adhesive.

These and further objects of the invention will be more readily apparent upon consideration of the drawings accompanying the present specification and forming a part thereof in which:

Fig. 1 is a fragmentary view in front perspective of apparatus made in accordance with the invention;

Fig. 2 is a view in plan of the brush making apparatus shown in Fig. 1;

Fig. 3 is a view in vertical cross-section through a portion of the apparatus shown in Figs. 1 and 2 the section being taken in the vicinity of the means for applying the bristle retaining strands or cords and the bristles to the core, the section being taken along the line 3—3, in Fig. 2;

Fig. 4 is a view in bottom plan of the cord and bristle applying wheel, the view being taken from a point of view along line 4—4 in Fig. 3;

Fig. 5 is a view in horizontal section through the apparatus above the cord and bristle applying wheel, the section through the supporting and driving shaft for

such wheel being taken along the line 5—5 in Fig. 3; and

Fig. 6 is a view in axial vertical section through the brush core in the vicinity of the zone in which bristles are applied thereto, the section being taken along the line 6—6 in Fig. 5.

As shown in Figs. 1 and 2, the basic structure of the brush forming apparatus of the invention may conveniently take the form of a lathe, generally designated by the reference character 2. Such lathe includes the parallel ways 4 on its bed, and a head stock 6 carrying a chuck 8, the head stock being rotatably driven by the belt 10 extending to a prime mover, not shown. Slidable longitudinally of the ways 4 is a carriage, generally designated 12, such carriage being constantly urged to the left, as the apparatus is shown in Figs. 1 and 2, by means such as the weight 14 which is connected to the carriage through the medium of the cable 16. Such cable extends over the guide sheave 18, affixed to the bed of the lathe, and is connected to the carriage at 20, as shown in Fig. 1.

The core 22 of the brush, which in this instance is in the form of a metal tube, is secured at one end by the chuck 8, the core being rotatably carried by the bushing 24 affixed to the left-hand edge of carriage 12, as shown in Figs. 5 and 6, such bushing serving as a slidable outboard bearing for the brush core. For ease of further description of the apparatus the operator for the machine will be considered hereinatter as standing at a position to the left of carriage 12 as the device is shown in Fig. 2. Portions of the apparatus at the operator's left, as he stands facing the brush being wound will be described as "left" and those at his right will be described as "right." Portions of the apparatus generally beyond the brush will be described as being to the rear, whereas those generally on the side of the brush adjacent the operator will be described as being located at the front of the apparatus.

As shown in Figs. 1 and 2, the carriage 12 is made up of two main supporting plate portions, the rear plate portion 26 and the front plate portion 28. The upper surfaces of such plates, which, as shown, are disposed horizontally, lie substantially flush with the upper surface of the brush core 22. Plates 26 and 28 are joined by bridge members spanning the brush core so as not to interfere with such core, one such bridge member being shown at 30 in Figs. 1 and 2, where it is depicted as being joined to the plates by studs. Plate portions 26 and 28 are further connected at the left by means of the bridge member 32 which includes a brush core engaging bore therethrough as a continuation of that through bushing member 24. Bridge member 32 is secured to the plates 26 and 28 by studs, of which one is shown at 34 in Fig. 6. The carriage structure 12 is supported upon ways 4 by means of the guiding support members 36 affixed to the bottom of plate 28. The bushing 24, previously described, is secured to the bridge member 32 by being positioned in the seat 38 in the left-hand edge of the latter, as shown in Fig. 6. Bushing 24 is terminated at its top in a plane flush with the top of core 22, as indicated at 130, to accommodate wheel 72, to be described.

The apparatus of the illustrated preferred embodiment of the present invention includes a dual-diameter bristle and bristle-securing cord feeding wheel which is positioned on the carriage in such position as to feed the cord entering upon the core in a direction generally tangential to the helix which such cord assumes when it is wrapped upon the core. The axis of such cord and bristle feeding wheel accordingly lies generally normal to the axis of the core, the axis of such wheel preferably substantially intercepting the axis of the core as shown, the wheel being positioned closely adjacent one side of the core.

The cord and bristle feeding wheel and its manner of support are more clearly shown in Figs. 3 to 6, inclusive. As there shown, there is provided a top horizontal member 40 which is secured to the carriage plate member 28 by means of the bolt 42, which has positioned thereabout the right spacer sleeve 44. Member 40 is further supported by means of the left stud member 46, which has positioned thereabout the left spacer sleeve 48. Stud 46

is screwed in to the lower wheel supporting member 50 which, as shown, is horizontal and likewise parallel to table member 28. Member 50 is further supported from the table by means of the interposed supporting spacer member 51, shown in Fig. 3. Members 40 and 50 carry journaled therebetween the right-hand vertical shaft 52, which carries on the top thereof the sheave 54 keyed thereto. To the left of sheave 54 there is positioned the idler sheave 56 which is supported from member 40 by means of the stub axle 58. The left-hand vertical shaft 60 is likewise journaled by means of supporting members 40 and 50. Shaft 60 carries on the top thereof the sheave 62 keyed thereto. Both shafts 52 and 60 are supported at the bottom thereof by ball bearings, such bearing for shaft 52 being designated 64 and that for shaft 60 being denoted 66. Shafts 52 and 60 are drivingly connected by means of the V belt 68 which is entrained around sheaves 54 and 62, the belt being tensioned by means of the idler sheave 56.

Shaft 52 carries on the bottom end thereof, below member 50, the sprocket 70 and the V-grooved sheave 150, subsequently to be more particularly described as to function. Shaft 60 carries on the bottom thereof, below member 50, the composite cord and bristle feeding applicator wheel, generally designated 72. Integral with the hub 74 of such wheel is the upper, larger diameter wheel portion 76 which, as more clearly shown in Fig. 4, is shallowly serrated on its periphery, to give it a more effective bristle feeding action. The teeth 78 on such periphery are, as shown, of square configuration, such teeth being separated by the notches or valleys 80 therebetween. The serrations on wheel portion 76 are not pronounced enough to cause the bristles as fed onto the brush core to lie in other than substantially continuous helices of substantially constant width.

The lower portion 82 of the composite wheel 72 is of a smaller diameter than portion 76, wheel portion 82 having a radius, as more clearly shown in Fig. 4, which is generally equal to that of wheel portion 76 measured to the bottom of a notch 80, minus the diameter of the bristle retaining cord. Wheel portion 82 is secured to the main portion of the wheel by means of the angularly spaced studs 84, as shown in Fig. 4. The periphery of the lower, smaller wheel portion 82 is serrated to provide the shallow, generally saw tooth shaped, serrations 86 thereon, the straight, radially disposed, walls of serrations 80 facing toward the direction from which the cord is fed to such wheel portion. Serrations 86 cause the cord unslippingly to grip the wheel portion 82.

In forming a cylindrical wound brush by the apparatus of the invention, there is provided on the brush core 22, at a position near the left-hand end thereof, the starting collar 88. Such collar is retained on the brush core as by means of a set screw shown at 90. Collar 88 is provided in one zone thereof with a helical cut 92 which receives the starting ends of the bristle retaining cord or cords employed. At the deepest portion of such helical cut there are provided bores 94 therethrough, one for each cord, the cord being passed through such bores and each provided with a knot at a position outside the collar, one such knot being shown at 96.

In the embodiment of the apparatus shown, there are employed two bristle retaining cords, one wound on top of the other. The bottom cord, which may be made of hemp or sisal, is designated 98. The upper cord, which it is preferred to make of stronger, more chemically resistant material such as twisted nylon, is designated 100. The bristles, designated 102, have their butt; inner ends 104 adjacent the core held between adjacent convolutions of such cords 98 and 100. The finished brush portion, that is, that with the cords wound thereon and the bristles held between adjacent helices of the cords, but with the thermosetting resin with which the cords and bristle ends 104 are impregnated not yet cured, is designated generally 106. It will be understood that after the brush has been fully wound, the ends of the strands at the right are secured, as by a further collar similar to collar 88, applied to the core. The brush is then placed in an oven to cure the resin impregnating the strands and the butt ends of the bristles.

As shown in Fig. 1, the cords 98 and 100 proceed from sources (not shown) over the respective guide sheaves 108, 108' downwardly through cord tensioning means. The cord tensioning means for cord 100 has its parts designated by the same reference characters as those em-

ployed in describing that for cord 98, but with an added prime. The tensioning means shown at the right in Fig. 1 consists of a fixed tensioning plate 110 affixed to the rear edge of plate 26 and the spring pressed movable plate 112, the cord 98 being compressed between such two plates. Plate 112 is thrust toward plate 110 by means of the compression springs 114 which surround headed studs which extend through plates 112 and 110 and are threaded into carriage plate portion 26. After leaving such cord tensioning means, each cord is then fed downwardly into a container containing a cord impregnating thermosetting resin which may be, for example, a phenol-formaldehyde or a urea-formaldehyde resin. Such container for cord 98 is designated 116, there being positioned at the bottom of the container a guide sheave 118 around which the cord runs, such sheave being journaled in fixed supporting structure not shown. The cord then rises from the container 116, passes around the guide sheave 120 above the container, and progresses to the cord applying portion 82 of the composite wheel 72. The similar parts acting upon cord 100, that is, the impregnating resin container, the guide sheave within the container, and the top cord guiding sheave, are designated by the same reference characters as those previously employed in designating the apparatus described for treating the cord 98, but with an added prime. Cord 100 occupies the upper position on wheel portion 82 and thus the outer position on the brush core whereas cord 98 occupies the lower position on the wheel portion 82 and the inner position on the brush core, as more clearly shown in Figs. 3 and 6.

The last complete helix of the cords wound upon the brush core is designated 122, as shown in Figs. 5 and 6. The left-hand face of bushing 24 is of such configuration that it contacts the last helix of the cord or cords including the portion thereof just entered upon the brush core, substantially over their entire extent. Such left-hand edge of bushing 24 is thus in the form of a helix, the portion thereof which contacts the last laid complete convolution of the cords being designated 124. At the top, the bushing 24 is flattened off flush with the upper surface of core 22 of the brush to allow the lower portion 82 of the composite wheel to rotate close to such upper surface of the brush core. At a position 40 beyond the composite applicator wheel, that is, above it as it is shown in Fig. 5, the helical face portion 128 of the bushing 24 is spaced to the right of the end of portion 124 of its face a distance generally equal to the diameter of the cord or cords employed, plus the width of 45 the bristle row caught between the convolutions of the cords. The entering helix of the cord, that is, that leaving portion 82 of the composite applicator wheel and first entering into engagement with the brush core, is designated 126.

50 Besides laying the cord accurately upon the brush core in the manner indicated, the composite wheel 72 also feeds between such entering portion 126 of the cord and the last previously completely laid helix of cord a substantially continuous row of bristles of predetermined width. The apparatus accomplishes such feeding of the row of bristles in the following manner. Portion 28 of carriage 12 is provided with a right-hand fixed bristle guide 132 which is elevated above the surface of part 28 on spacer sleeves of which one is shown at 133 in Fig. 1, being retained in such elevated position parallel to the upper surface of part 28 by studs 135 extending through the spacer sleeves into part 28. The rear left-hand corner guide 132 extends almost into contact with the periphery of portion 76 of wheels 72. Guide 132 is of the same thickness as wheel portion 76 and lies on the same level as such wheel portion.

55 Also affixed to plate 28 is the left-hand fixed bristle guide member 134 which is positioned parallel to member 132 but spaced therefrom so as to form a bristle feeding channel therebetween. Member 134 is of the same thickness as, and is retained at the same horizontal level above part 28 as, guide 132, by means of the Z-shaped bracket 137 at the front end of member 134 and the spacer sleeve 133 and stud 135 intermediate the ends of member 134, as shown in Fig. 1. The channel between guide members 132 and 134 is, as shown, directed substantially radially of the shaft 60 and wheel 72.

60 The spacing between bristle guiding members 132 and 134 and plate 28 is such as to provide space between 65 134 and plate 28 as to provide space between

such bristle guiding members and the upper surface of plate 28 sufficient for the reception of two bristle feeding chains and for a portion of the supporting and driving mechanism therefor. The right-hand bristle feeding chain is designated 136. Such chain is entrained about the previously described sprocket 70 on shaft 52, the rear left sprocket 138, and the front sprocket 140, such sprockets being positioned above part 28 and carried on stub shafts journaled in such part. Sprockets 138 and 140 are positioned so as to provide a run of the chain parallel with, and projecting slightly outwardly from beneath, the left-hand edge of the bristle feeding guide 132. The left-hand bristle feeding chain, associated with fixed bristle guide member 134, is designated 142. Chain 142 is entrained over the rear sprocket 144, the front central sprocket 148, and the front left sprocket 146, sprockets 144 and 148 being so positioned as to provide a straight run of the chain parallel with and projecting slightly outwardly from beneath the right-hand edge of bristle guiding member 134. Sprockets 144, 146, and 148 are positioned with respect to, and supported in the same manner on carriage part 28 as, sprockets 138 and 140.

Chains 136 and 142 are driven in the direction shown by the arrows in Fig. 2, so as to impel stacks of bristles positioned between members 132 and 134 toward the feeding wheel 72. Such drive is effected by means of the crossed V belt which is entrained about the previously described sheave 150 on shaft 52, a sheave 154 connected to sprocket 140, and a sheave 156 connected to sprocket 146, the V belt being crossed as it passes around sheave 156. All such sheaves are located on the same horizontal level, the sheaves 154 and 156 lying above carriage part 28 and beneath their respective sprockets. Such V belt is designated 152.

To assist the chains 136 and 142 in their feeding of bristles toward the applicator wheel, there are also provided the following reciprocating bristle feeding mechanisms. As shown in Fig. 2, there is positioned on top of the front right portion of table member 28 the freely swinging block member 160 which is connected to member 28 by means of the rod 162, such rod being pivoted to the table at a position forwardly of the apparatus beyond the confines of Fig. 2. Block member 160 guides the reciprocable bristle feeding member 164 through the medium of the longitudinal guide means 166 between such members. Member 164 has projecting from the left-hand edge thereof the bristle feeding finger 168 which overlies the right-hand edge of bristle guiding member 134.

Elements 160 to 168, inclusive, are employed as follows: a bundle of bristles of the proper length, temporarily held together as by a rubber band positioned about the top of the bundle, is placed against the right-hand edge of member 134, the member 160 being at that time in retracted position to the right. Thereupon member 160 is swung to the left, by means of the upstanding handle provided thereon, to grip such bundle of bristles between members 134 and 164, whereupon the rubber band may be removed. The block 164 may then be thrust to the rear to cause the bristles to travel between members 132 and 134 and into gripping relationship with the bristle conveying chains 136 and 142.

To assist such chains in their feeding action and to provide a positive feeding action upon the bristles, there is provided a further reciprocating bristle feeding mechanism. Such mechanism takes the form of the reciprocable feeder member 170 which, as shown, has on its left-hand edge the depending flange 172. Flange 172 engages the left-hand edge of the guiding member 134. A push rod 176 is connected, as shown, to the left-hand forward corner of member 170, such push rod extending through a bore in the freely rotatable vertically disposed guiding post 178 mounted on carriage part 28. Connected to the front end of push rod 176 is the cross arm 180, to the left-hand end of which is secured the cord 182 which runs over the guide sheave 184 affixed to the bottom part of carriage plate 28. A weight (not shown) is secured to such vertical cord portion, thereby constantly urging feeder member 170 rearwardly.

It will be apparent that such supporting and guiding structure for reciprocating feeder 170 allows it intermittently freely to be retracted to the left, after it has substantially reached wheel 82, pulled forwardly, and then placed into engagement with the forward end of a fresh

group of bristles fed into the guide channel. It may, however, be placed in the position shown and is then stably held by reason of the angular disposition of the push rod 176 with respect thereto. When in such position, block 170 exerts a constant rearward feeding action upon the bristles in the rear portion of the guide channel between members 132 and 134 by reason of the engagement of such bristles by the laterally projecting finger 186 on block 170, such finger overlying the left-hand edge of guide member 132.

The bristles 102, fed toward the applicator wheel between the left-hand edge 186 of member 132 and the right-hand edge 158 of member 134, are engaged by the teeth 78 on the bristle feeding portion 76 of such wheel, and are impelled to the left in a curved path by such wheel to assume a position between the last completely wound convolution of cord or cords on the brush core and the entering portion 126 of the cord just being fed on to the core. The rear portion of guide member 134 is formed with a curved edge 188 concentric with the periphery of the wheel 76 and spaced therefrom the desired distance to give the predetermined width to the substantially continuous row of bristles to be secured between convolutions of the cord. As previously explained, the bristle guiding members 132 and 134 are positioned at the same level as the upper, bristle feeding, portion 76 of the composite feeding wheel. Such rear curved edge 188 of member 134 is terminated at a point 190, shown more clearly in Fig. 5, where there is sufficient engagement between the bristles being fed and the two convolutions 122 and 126 of the cord to insure their subsequent stable positioning on the brush core.

In order to insure the removal of stray bristles from the feeding wheel, which bristles may not have been sufficiently engaged between the cords on the brush core to remove them from the wheel portions 76, there is provided the stripper finger 192 supported, as shown in Fig. 2, from the vertical post 194 mounted on carriage part 26. Such stripper finger lies beneath the wheel portion 76 and substantially in contact with the periphery of the lower wheel portion 82, whereby it cams away from the wheel any of the described stray bristles which have not been applied to the brush.

It will be seen from the above description that the apparatus of the present invention is characterized by its simplicity when compared to previously known devices for making cylindrical wound brushes. The action of the device is smooth and fast, since no rapidly reciprocating members for feeding the bristles are employed, such feeding being done by a smoothly and steadily rotating wheel. In the described preferred embodiment of the apparatus, the drive for the composite cord and bristle applying wheel, as well as for the bristle feeding chains in the channel leading to such wheel, is derived solely from the winding of the cord or cords upon the brush core, such cord or cords, by reason of their frictional engagement with the serrated periphery of the wheel 82, driving such wheel, and, through the medium of the described sheaves and V belt, the bristle feeding chains in the channel leading to the applicator wheel. As a result, perfect synchronism of the parts is constantly maintained, it being impossible for the apparatus to deliver the bristles to the brush core at any but the predetermined rate.

Whereas for purposes of illustration I have shown and described a preferred embodiment of the apparatus for making brushes of my invention, it will be understood that such embodiment is illustrative only, and that the apparatus is capable of considerable variation as to details. The invention is, therefore, to be defined by the scope of the claims appended hereto.

I claim as new the following:

1. In a machine for making brushes, said machine having in combination a brush core rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, a strand applying means mounted on the carriage, a wheel mounted on the carriage adjacent said last named means, said wheel having a bristle feeding periphery, means for supplying bristles to the bristle feeding periphery of the wheel, means forming with the bristle feeding periphery of the wheel a bristle conducting passage extending from the bristle supplying means sub-

7. In a machine for making brushes, said machine having in combination a brush core, means for substantially directly to the brush core, between the last complete turn of the coil of the strand and the portion of the strand, at its first engagement with the core, and means to turn the wheel at a speed synchronized with that of the brush core.

8. In a machine for making brushes, said machine having in combination a brush core, rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, a strand applying means mounted on the carriage, a wheel mounted on the carriage adjacent said last named means, said wheel having a bristle feeding periphery lying at least generally tangential to the row of bristles last laid on the brush core, a bristle guiding means on the means for supplying bristles to the bristle feeding periphery of the wheel, means forming with the bristle feeding periphery of the wheel a curved bristle conducting passage from the bristle supplying means to the brush core between the last complete turn of the coil of the strand and the portion of the strand, at its first engagement with the core, and means to drive the wheel in the same relative direction as the brush core and at such speed that the peripheral speed thereof is substantially equal to the peripheral speed of the brush core.

9. In a machine for making brushes, said machine having in combination a brush core, rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, a strand applying means mounted on the carriage and positioned adjacent one side of the core, a bristle applying wheel mounted on the carriage adjacent said last named means, the axis of the wheel lying generally normal to the axis of the core, said wheel having a bristle feeding periphery lying at least generally tangential to the row of bristles last laid on the brush core, a bristle guiding means on the carriage leading to the bristle feeding periphery of the wheel, means forming with the bristle feeding periphery of the wheel a curved bristle conducting passage from the bristle guiding means substantially directly to the brush core between the last complete turn of the coil of the strand and the portion of the strand at its first engagement with the core, and means to drive the wheel in the same relative direction as the brush core and at such speed that the peripheral speed thereof is substantially equal to the peripheral speed of the brush core.

10. In a machine for making brushes, said machine having in combination a brush core, rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, a strand and bristle applying wheel mounted on the carriage and positioned adjacent one side of the core, the axis of the wheel lying generally normal to the axis of the core, said wheel having a first portion for engagement with the strand as it is led on to the brush core, the edge of such first portion of the wheel nearest the strand in that portion thereof first engaging the brush core being substantially tangential to the entering end of such first turn, said wheel having a second bristle feeding portion, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel.

11. In a machine for making brushes, said machine having in combination a core, rotating element, means for supplying a strand for the formation of a coil on the brush core and for feeding bristles between the turns of the coil during the rotation of the core, the improvement in said last named means which comprises a carriage

12. mounted for movement along the brush core parallel with the axis thereof, said carriage having connected thereto a block, means constantly urging the carriage in such direction as to maintain lateral compression by the block on the turns of the strand on the core, a strand and bristle applying wheel mounted on the carriage and positioned adjacent one side of the core, the axis of the wheel lying generally normal to the axis of the core, said wheel being positioned adjacent the surface of the brush core, the wheel having a first portion for engagement with the strand as it is led on to the brush core, the edge of such first portion of the wheel nearest the strand first engaging the brush core being tangential to the entering end of such first turn, the strand engaging such first portion of the wheel over a substantial angular extent, means for imposing a substantial retarding tension on the strand in that portion thereof leading to the wheel, said wheel having a second, larger diameter, portion lying outwardly of the first portion of the wheel with respect to the brush core, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel.

13. In a machine for making brushes, said machine having in combination a brush core, rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, said carriage having connected thereto a block, means constantly urging the carriage in such direction as to maintain lateral compression by the block on the turns of the strand on the core, a strand and bristle applying wheel mounted on the carriage and positioned adjacent one side of the core, the axis of the wheel lying generally normal to the axis of the core, said wheel having a first portion adjacent the surface of the brush core for engagement with the strand as it is led on to the brush core, the edge of such first portion of the wheel nearest the strand in that portion thereof first engaging the brush core being generally tangential to the entering end of such first turn of the coil, the strand engaging such first portion of the wheel over a substantial angular extent, said wheel having a second portion lying outwardly of the first portion of the wheel with respect to the brush core, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at substantially its first engagement with the core, the winding of the strand by the core and its engagement with the first portion of the wheel serving as the sole source of motive power to turn such wheel.

14. In a machine for making brushes, said machine having in combination a brush core, rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, said carriage having connected thereto a block, means constantly urging the carriage in such direction as to maintain lateral compression by the block on the turns of the strand on the core, a strand and bristle applying wheel mounted on the carriage and positioned adjacent one side of the core, the axis of the wheel lying substantially normal to the axis of the core, said wheel having a first, smaller diameter, portion adjacent the surface of the brush core for engagement with the strand as it is led on to the brush core, the edge of such first portion of the wheel nearest the strand in that portion thereof first engaging the brush core being generally tangential to the entering end of the first turn of the coil, the strand engaging such first portion

tion of the wheel over a substantial angular extent, said wheel having a second, larger diameter, portion lying outwardly of the first portion of the wheel with respect to the brush core, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel.

8. In a machine for making brushes, said machine having in combination a brush core rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, said carriage having connected thereto a block, means constantly urging the carriage in such direction as to maintain lateral compression by the block on the turns of the strand on the core, a strand and bristle applying wheel mounted on the carriage and positioned adjacent one side of the core, the axis of the wheel lying generally normal to the axis of the core, said wheel having a first, smaller diameter, portion adjacent the surface of the brush core, for engagement with the strand as it is led on to the brush core, the edge of such first portion of the wheel nearest the strand in that portion thereof first engaging the brush core being generally tangential to the entering end of such first turn of the coil, the strand engaging such first portion of the wheel over a substantial angular extent, means for imposing a substantial retarding tension on the strand in that portion thereof leading to the wheel, said wheel having a second, larger diameter, portion lying outwardly of the first portion of the wheel with respect to the brush core, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel.

9. In a machine for making brushes, said machine having in combination a brush core rotating element, means for supplying a strand for the formation of a coil on the brush core and for feeding bristles between the turns of the coil during the rotation of the brush core, the improvement in said last named means which comprises a carriage mounted for movement along the brush core parallel with the axis thereof, said carriage having connected thereto a bushing surrounding the as yet unwrapped brush core, means constantly urging the carriage in such direction as to maintain lateral compression by the bushing on the turns of the strands on the core, a strand and bristle applying wheel rotatably mounted on the carriage and positioned adjacent one side of the core with the strand and bristle applying portions of the wheel lying adjacent the strand contacting side of the bushing, the axis of the wheel lying substantially normal to the axis of the brush core, said wheel having a first, smaller diameter, portion adjacent the surface of the brush core for engagement with the strand as it is led on to the brush core, the edge of such first portion of the wheel nearest the strand in that portion thereof first engaging the brush core being tangential to the entering end of such first turn of the coil, the strand engaging such first portion of the wheel over a substantial angular extent, means for imposing a substantial retarding tension on the strand in that portion thereof leading to the wheel, said wheel having a second, larger diameter, portion lying outwardly of the first portion of the wheel with respect to the brush core, a bristle guiding and feeding means on the carriage leading to the periphery of the second portion of the wheel, means forming with the second portion of the wheel a curved bristle conducting passage from the bristle guiding and feeding means to the brush core between the last complete turn of the coil of strand and the portion of the strand at its first engagement with the brush core, means forming with the second portion of the wheel a curved bristle conducting passage from the bristle guiding and feeding means to the brush core between the last complete turn of the coil of strand and the portion of the strand at its first engagement with the brush core.

ment with the brush core, means driving the bristle guiding and feeding means from and in synchronism with the strand and bristle feeding wheel, the winding of the strand by the brush core and the engagement of such strand with the first portion of the wheel serving as the sole source of motive power to turn the wheel and to drive such bristle guiding and feeding means.

10. In a machine for making brushes, said machine having in combination a brush core rotating element, means for supplying a strand for the formation of a coil on the brush core and for feeding bristles between the turns of the coil during the rotation of the brush core, the improvement in said last named means which comprises a carriage mounted for movement along the brush core parallel with the axis thereof, said carriage having connected thereto a bushing surrounding the as yet unwrapped brush core, means constantly urging the carriage in such direction as to maintain lateral compression by the bushing on the turns of the strands on the core, a strand and bristle applying wheel rotatably mounted on the carriage and positioned adjacent one side of the core with the strand and bristle applying portions of the wheel lying adjacent the strand contacting side of the bushing, the axis of the wheel substantially intersecting the axis of the core and lying substantially normal thereto, said wheel having a first, smaller diameter, portion adjacent the surface of the brush core, for engagement with the strand as it is led on to the brush core, the edge of such first portion of the wheel nearest the strand in that portion thereof first engaging the brush core being tangential to the entering end of such first turn of the coil, the strand engaging such first portion of the wheel over a substantial angular extent but for less than 360° , means for imposing a substantial retarding tension on the strand in that portion thereof leading to the wheel, means between the tension imposing means for the strand and the strand and bristle applying wheel for immersing such strand in, and thus impregnating it with, a heat curable adhesive material, said wheel having a second, larger diameter, portion lying outwardly of the first portion of the wheel with respect to the brush core, a bristle guiding means on the carriage leading to the periphery of the second portion of the wheel, said last named means comprising spaced parallel members having a bristle guiding channel between them, the channel being disposed substantially radially of the wheel, a bristle feeding means comprising two elongated flexible members, guide sheaves for each of such flexible members, each such flexible member having a straight portion disposed adjacent its respective edge of the channel so as to engage bristles in such channel, means on the end of one of the spaced parallel members forming with the second portion of the wheel a curved bristle conducting passage from the bristle conducting channel to the brush core between the last complete turn of the coil of strand and the portion of the strand at its first engagement with the brush core, means driving the flexible bristle feeding members from and in synchronism with the strand and bristle feeding wheel, the winding of the strand by the brush core and the engagement of such strand with the first portion of the wheel serving as the sole source of motive power to turn the wheel and to drive such elongated flexible bristle feeding members.

11. In a machine for making brushes, said machine having in combination a brush core rotating element, means for supplying a plurality of strands, one on top of the other, for the formation of a plurality of superimposed coils on the brush core and for feeding bristles between the superimposed turns of the coils during the rotation of the brush core, the improvement in said last named means which comprises a carriage mounted for movement along the brush core parallel with the axis thereof, said carriage having connected thereto a bushing surrounding the as yet unwrapped brush core, means constantly urging the carriage in such direction as to maintain lateral compression by the bushing on the turns of the strands on the core, a strand and bristle applying wheel rotatably mounted on the carriage and positioned adjacent one side of the core with the strand and bristle applying portions of the wheel lying adjacent the strand contacting side of the bushing, the axis of the wheel substantially intersecting the axis of the core and lying substantially normal thereto, said wheel having a first, smaller diameter, portion adjacent the surface of the brush core, for engagement with the strands as they are led on to the

brush core, the edge of such first portion of the wheel nearest the strands in that portion thereof first engaging the brush core being tangential to the entering ends of such first superimposed turns of the coils, the strands engaging such first portion of the wheel over a substantial angular extent but for less than 360° , means for imposing a substantial retarding tension on each of the strands in that portion of each leading to the wheel, and means between the tension imposing means for each of the strands and the strand and bristle applying wheel for immersing such strands in, and thus impregnating them with, a heat curable adhesive material, said wheel having a second, larger diameter, portion lying outwardly of the first portion of the wheel with respect to the brush core, the periphery of such second portion of the wheel being shallowly serrated, a bristle guiding means on the carriage leading to the periphery of the second portion of the wheel, said last named means comprising spaced parallel members having a bristle guiding channel between them, the channel being disposed substantially radially of the wheel, a second bristle feeding means comprising two elongated flexible members, guide sheaves for each of such flexible members, each such flexible member having a straight portion disposed adjacent its respective edge of the channel so as to engage bristles in such channel, means on the end of one of the spaced parallel members forming with the second portion of the wheel a curved bristle conducting passage from the bristle conducting channel to the brush core between the last complete turn of each of the coils of strands and the portion of each strand at its first engagement with the brush core or with the corresponding turn of the strand spaced inwardly of the brush core, means driving the flexible bristle feeding members from and in synchronism with the strand and bristle feeding wheel, the winding of the strands by the brush core and the engagement of such strands with the first portion of the wheel serving as the sole source of motive power to turn the wheel and to drive such elongated flexible bristle feeding members.

12. In a machine for making brushes, said machine having in combination a brush core rotating element, means for supplying a plurality of strands, one on top of the other, for the formation of a plurality of superimposed coils on the brush core and for feeding bristles between the superimposed turns of the coils during the rotation of the brush core, the improvement in said last named means which comprises a carriage mounted for movement along the brush core parallel with the axis thereof, said carriage having connected thereto a bushing surrounding the as yet unwrapped brush core, means constantly urging the carriage in such direction as to maintain lateral compression by the bushing on the turns of the strands on the core, a strand and bristle applying wheel rotatably mounted on the carriage and positioned adjacent one side of the core with the strand and bristle applying portions of the wheel lying adjacent the strand contacting side of the bushing, the axis of the wheel substantially intersecting the axis of the core and lying substantially normal thereto, said wheel having a first, smaller diameter, portion adjacent the surface of the brush core, for engagement with the strands as they are led on to the brush core, the edge of such first portion of the wheel nearest the strands in that portion thereof first engaging the brush core being shallowly serrated and being tangential to the entering ends of such first superimposed turns of the coils, the strands engaging such first portion of the wheel over a substantial angular extent but for less than 360° , means for imposing a substantial retarding tension on each of the strands in that portion of each leading to the wheel, and a separate means between the tension imposing means for each of the strands and the strand and bristle applying wheel for immersing such strand in, and thus impregnating it with, a heat curable adhesive material, said wheel having a second, larger diameter, portion lying outwardly of the first portion of the wheel with respect to the brush core, the periphery of such second portion of the wheel being shallowly serrated, a bristle guiding means on the carriage leading to the periphery of the second portion of the wheel, said last named means comprising spaced parallel members having a bristle guiding channel between them, the channel being disposed substantially radially of the wheel, a first bristle feeding means located at the end of the channel

remote from the wheel, said first feeding means comprising a bristle engaging means reciprocable longitudinally of the channel, a second bristle feeding means comprising two elongated flexible members, guide sheaves for each of such flexible members, each such flexible member having a straight portion disposed adjacent its respective edge of the channel so as to engage bristles in such channel, the first recited bristle feeding means forwarding bristles into engagement with the elongated flexible members, means on the end of one of the spaced parallel members forming with the second portion of the wheel a curved bristle conducting passage from the bristle conducting channel to the brush core between the last complete turn of each of the coils of strands and the portion of each strand at its first engagement with the brush core or with the corresponding turn of the strand spaced inwardly of the brush core, means driving the flexible bristle feeding members from and in synchronism with the strand and bristle feeding wheel, the winding of the strands by the brush core and the engagement of such strands with the first portion of the wheel serving as the sole source of motive power to turn the wheel and to drive such elongated flexible bristle feeding members.

13. In a machine for making brushes, said machine having in combination a brush core rotating element, means for supplying a strand for the formation of a coil on the brush core and for feeding bristles between the turns of the coil during the rotation of the core, the improvement in the last named means which comprises a support mounted adjacent the brush core, means for moving the brush core and the support relative to each other along a path parallel to the axis of the core, a strand applying means mounted on the support, a wheel mounted on the support adjacent said last named means, said wheel having a bristle feeding periphery lying at least generally tangential to the row of bristles last laid on the brush core, means for supplying bristles to the bristle feeding periphery of the wheel, means forming with the bristle feeding periphery of the wheel a bristle conducting passage extending from the bristle supplying means substantially directly to the brush core between the last complete turn of the coil of the strand and the portion of the strand at its first engagement with the core, and means to drive the wheel in the same relative direction as the brush core and at a speed synchronized with that of the brush core.

14. In a machine for making brushes, said machine having in combination a brush core rotating element, means for supplying a strand for the formation of a coil on the brush core and for feeding bristles between the turns of the coil during the rotation of the core, the improvement in said last named means which comprises a support mounted adjacent the brush core, means for moving the brush core and the support relative to each other along a path parallel to the axis of the core, a strand applying means mounted on the support, a wheel mounted on the support adjacent such last named means, said wheel having a bristle feeding periphery lying at least generally tangential to the row of bristles last laid on the brush core, means for supplying bristles to the bristle feeding periphery of the wheel, means forming with the bristle feeding periphery of the wheel a curved bristle conducting passage extending from the bristle supplying means substantially directly to the brush core between the last complete turn of the coil of the strand and the portion of the strand at its first engagement with the core, and means to drive the wheel in the same relative direction as the brush core and at a speed synchronized with that of the brush core.

15. In a machine for making brushes, said machine having in combination a brush core rotating element, means for supplying a strand for the formation of a coil on the brush core and for feeding bristles between the turns of the coil during the rotation of the core, the improvement in said last named means which comprises a support mounted adjacent the brush core, means for moving the brush core and the support relative to each other along a path parallel to the axis of the core, a strand and bristle applying wheel mounted on the support and positioned adjacent one side of the core, the axis of the wheel lying in a plane extending at right angles to the axis of the brush core, said wheel having a first portion for engagement with the strand as it is led on to the brush core, the edge of such first portion of the

wheel nearest the strand in that portion thereof first engaging the brush core lying substantially along a line tangential to the entering end of such first turn, said wheel having a second, bristle feeding, portion, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel, the second bristle feeding portion of the wheel rotating in the same relative direction as, and at a speed synchronized with the speed of, the brush core.

16. In a machine for making brushes, said machine having in combination a core rotating element, means for supplying a strand for the formation of a coil on the brush core and for feeding bristles between the turns of the coil during the rotation of the core, the improvement in said last named means which comprises a carriage mounted for movement along the brush core parallel with the axis thereof, said carriage having connected thereto a block, means constantly urging the carriage in such direction as to maintain lateral compression by the block on the turns of the strand on the core, a strand and bristle applying wheel mounted on the carriage and positioned adjacent one side of the core, the axis of the wheel lying in a plane extending at right angles to the axis of the brush core, said wheel being positioned adjacent the surface of the brush core, the wheel having a first portion for engagement with the strand as it is led on to the brush core, the edge of such first portion of the wheel nearest the strand in that portion thereof first engaging the brush core lying substantially along a line tangential to the entering end of such first turn, the strand engaging such first portion of the wheel over a substantial angular extent, means for imposing a substantial retarding tension on the strand in that portion thereof leading to the wheel, said wheel having a second, larger diameter, portion lying outwardly of the first portion of the wheel with respect to the brush core, a bristle guiding means on the carriage leading to the periphery of the second portion of the wheel, means forming with the second portion of the wheel a curved bristle conducting passage from the bristle guiding means to the brush core between the last complete turn of the coil of the strand and the portion of the strand at its first engagement with the core, the winding of the strand by the core and its engagement with the first portion of the wheel serving as the sole source of motive power to turn such wheel, the rotation of the second portion of the wheel being in the same direction as, and at a speed synchronized with that of, the brush core.

17. In a machine for making brushes, said machine having in combination a brush core rotating element, means for supplying a strand for the formation of a coil on the brush core and for feeding bristles between the turns of the coil during the rotation of the core, the improvement in said last named means which comprises a support mounted adjacent the brush core, means for moving the brush core and the support relative to each other along a path parallel to the axis of the core, a strand applying means mounted on the support, a wheel mounted on the support adjacent said last named means, said wheel having a bristle feeding periphery, means for supplying bristles to the bristle feeding periphery of the wheel, means forming with the bristle feeding periphery of the wheel a curved bristle conducting passage from the bristle supplying means to the brush core between the last complete turn of the coil of the strand and the portion of the strand at its first engagement with the core, and means drivingly engaged by the strand as it is led to the brush core, said last named means being connected to the wheel to drive the wheel in the same relative direction as the brush core and at a speed synchronized with that of the brush core.

18. In a machine for making brushes, said machine having in combination a brush core rotating element, means for supplying a strand for the formation of a coil on the brush core and for feeding bristles between the turns of the coil during the rotation of the core, the improvement in the last named means which comprises a support mounted closely adjacent the brush core, means

for moving the brush core and the support relative to each other along a path parallel to the axis of the core, a strand applying means mounted on the support, a wheel mounted on the support adjacent said last named means, 5 said wheel having a bristle feeding periphery, means for supplying bristles to the bristle feeding periphery of the wheel, the bristle feeding periphery of the wheel forwarding bristles substantially directly to the brush core between the last complete turn of the coil of the strand and the portion of the strand at its first engagement with the core, one portion of the periphery of the bristle feeding wheel lying closely adjacent and generally tangential to the row of bristles last laid on the brush core, the axis of the bristle feeding wheel lying at a marked angle with respect to the axis of the brush core, and means to drive the bristle feeding wheel in the same relative direction as the brush core and at a speed synchronized with that of the brush core.

19. In a machine for making brushes, said machine 20 having in combination a brush core rotating element, means for supplying a strand for the formation of a coil on the brush core and for feeding bristles between the turns of the coil during the rotation of the core, the improvement in the last named means which comprises a 25 support mounted closely adjacent the brush core, means for moving the brush core and the support relative to each other along the path parallel to the axis of the core, a strand applying means mounted on the support, a wheel mounted on the support adjacent said last named means, 30 said wheel having a bristle feeding periphery, means for supplying bristles to the bristle feeding periphery of the wheel, means forming with the bristle feeding periphery of the wheel a bristle conducting passage extending from the bristle supplying means substantially directly to the brush core between the last complete turn of the coil 35 of the strand and the portion of the strand at its first engagement with the core, one portion of the periphery of the bristle feeding wheel lying closely adjacent and generally tangential to the row of bristles last laid on the brush core, the axis of the bristle feeding wheel lying at an angle which is in the neighborhood of a right angle with respect to the axis of the brush core, the axis of the bristle feeding wheel lying at least close to a radial plane through the brush core, and means to drive the wheel in the 40 same relative direction as the brush core and at a speed synchronized with that of the brush core.

20. In a machine for making brushes, said machine having in combination a brush core rotating element, 50 means for supplying a strand for the formation of a coil on the brush core and for feeding bristles between the turns of the coil during the rotation of the core, the improvement in the last named means which comprises a support mounted closely adjacent the brush core, means for moving the brush core and the support relative to each other along a path parallel to the axis of the core, a strand applying wheel mounted on the support, a bristle feeding wheel mounted on the support adjacent the strand applying wheel and at least generally coaxial therewith, said bristle feeding wheel having a bristle 55 feeding periphery, means for supplying bristles to the periphery of the bristle feeding wheel, the periphery of the bristle feeding wheel forwarding bristles substantially directly to the brush core between the last complete turn of the coil of the strand and the portion of the strand at its first engagement with the core, one portion of the periphery of the bristle feeding wheel lying closely adjacent and generally tangential to the row of bristles last laid on the brush core, the axes of the strand applying wheel and of the bristle feeding wheel lying at an angle 60 which is in the neighborhood of a right angle with respect to the axis of the brush core, the axis of the bristle feeding wheel lying at least close to a radial plane through the brush core, and means to drive the bristle feeding wheel in the same relative direction as the brush core and at a speed synchronized with that of the brush core.
